(57) **CLAIM**

An ornamental design for a tool body as shown and described.

DESCRIPTION

FIG. 1 is a rear perspective view of a tool body with a waste processing tool illustrated in broken line.

FIG. 2 is a rear perspective view of the tool body.

FIG. 3 is a front perspective view of the tool body.

FIG. 4 is a right side elevational view of the tool body of FIG. 2.

FIG. 5 is a left side elevational view of the tool body of FIG. 2.

FIG. 6 is a rear elevational view of the tool body of FIG. 2.

FIG. 7 is a front elevational view of the tool body of FIG. 2.

FIG. 8 is a top plan view of the tool body of FIG. 2; and, FIG. 9 is a bottom plan view of the tool body of FIG. 2. The broken lines shown in the drawings illustrate environment and form no part of the claimed design.
